F. W. VODOZ.
LUBRICATOR CUP AND INSERTABLE CONTAINER,
APPLICATION FILED NOV. 8, 1920.

Patented Apr. 11, 1922.

— Inventor:
Frederick W. Vodoz

By Josee Bain Thirkle

Atty's.

UNITED STATES PATENT OFFICE.

FREDERICK W. VODOZ, OF CHICAGO, ILLINOIS.

LUBRICATOR CUP AND INSERTABLE CONTAINER.

1,412,638.

Specification of Letters Patent. Patented Apr. 11, 1922.

Application filed November 8, 1920. Serial No. 422,470.

To all whom it may concern:

Be it known that I, FREDERICK W. VODOZ, a citizen of the United States, residing at Chicago, in the county of Cook and State of Illinois, have invented certain new and useful Improvements in Lubricator Cups and Insertable Containers, of which the following is a specification.

This invention relates to lubricator cups and insertable containers.

One of the objects of the invention is to improve cups to render them more economical, tidy and efficient.

Another object is to protect the contents of the cup from dirt and grit.

Another object is to provide a sealed collapsible container as a shipping package within which to hold grease or oil, for insertion within a cup, the contents of which is not exposed outside of the cup.

Another object is to provide a new form of collapsible, lubricant-container, in co-operation with the cup within which it is to be inserted for use.

Other, further and more specific objects of the invention will become readily apparent, to persons skilled in the art, from a consideration of the following description, when taken in conjunction with the drawings, wherein:

Fig. 1 is an elevation of the improved cup.

Fig. 2 is a central axial section thereof.

Fig. 3 is a plan view of a follower for the piston.

Fig. 4 is a central section thereof.

Fig. 5 is an end and side elevation of a valve within the stem of the cup.

Fig. 6 is an elevation of the sealed container for holding the lubricant, while in transit and in use.

Fig. 7 is an inverted end view thereof.

Fig. 8 is a plan view of the spring closure for the container.

Fig. 9 is an elevation thereof.

Fig. 10 is a key to advance the plunger in the cup to express the lubricant from the container.

In all the views the same reference characters are employed to indicate similar parts.

15 is the main body part of the cup, outwardly flared and enlarged at the bottom, as at 16, having an internal threaded opening 17 to provide an oblique shoulder between the two diameters. The cup is closed at the 55 top except for the inturned hub 18 which is screw threaded, as at 19, for the threaded

piston rod or stem 20. Stem 20 carries on its inner end a piston, or plunger 21, secured to which is a cup leather 22 and a follower 23. The parts mentioned are held in place by a 60 nut 24, the lower end of the stem 20 being reduced, as at 25, and headed at 26.

A key 27, having a rectangular end 28, is insertable in the notch or slot 29 of the stem 20, for the purpose of rotating the stem and 65 advancing the plunger into the cup.

The grease, or lubricant container 30, is made preferably, of collapsible material, such as thin sheet lead or an alloy thereof, having inserted at one end a relatively thick 70 and strong disc 31 which is downturned at its end as at 32. The material 33, of which the container is made, is turned around the downturned edge 32, as at 34.

A spring closure 35 is insertable in the 75 open end 35' of the container to close the container and to hold the contents therein during transit. The contents may be either oil or grease.

The lower end of the cup 15 is closed by a 80 disc 36, downturned as at 37, at its edges to form an oblique shoulder at its periphery, and threaded, as at 38, for screwing into the threaded part 17 of the cup. Disc 37 is provided with an internally threaded hub 39 85 within which is a stem or fitting 40. The lower end of the fitting is threaded, as at 41, for insertion into a bearing or box to be lubricated.

If oil is to be used in the container 30, 90 then a valve 42 is placed in the bore 43 of the fitting 40. The valve is provided with a reduced portion 43 which normally is in the bore 44 of the fitting 40. The valve is held closed by the spring 44 that rests upon a 95 sleeve 45 within the fitting. A relatively soft washer 46, constituting a packing, is located between the disc 31 of the container and the cap 36 of the cup, to prevent all of the contents of the container from passing 100 out from the interior of the cup.

Grease or oil is placed in the container 30 and the closure 35 is put into the opening 35' to prevent escape of the contents of the container. When the container is received 105 from the closure 36. The piston 21 is retracted by rotating the stem 20 in the proper direction. The container is then placed within the cup and the closure 35 is removed 110 from the opening 35'. The cup 15 is then screwed onto the end 36, whereupon the ta-

pered portion 15' of the cup will engage the overlying edges 34 of the container and squeeze the edges into close contact with the downturned edge 32 of the disc 31. This will insure the joint between the bottom wall or disc 31 and the side walls 33 in the container. Now, when the contents of the container is to be forced into the bearing, the stem 29 is rotated by the key 27. This has the effect to contract the collapsible container 30 and force the oil or grease out through the opening at the lower end of the sleeve 45 and into the bearing. If oil is to be used the valve 42 is well adapted for the purpose and the rotation of the threaded stem 20 will force a quantity of oil out of the container and into the space in which the valve 42 and the spring 44 are located, available for the bearing. If grease is to be used, valve 42 is not essentially necessary and the space will be filled with grease, the grease being less mobile than the oil, a special valve to maintain it in the container until required in the bearing, is not of so much importance.

When the threaded stem 20 is rotated the lubricating contents of the container must pass out through the lower end of the valve and not any of it will leak into the cup, and after the container has been entirely collapsed, there is no evidence in the cup that a lubricant has been contained therein, and therefore, the cup is clean and the lubricant is protected from contact with dirt or grit of any character. After the container has been entirely emptied and collapsed, it can easily be removed from the cup because of the fact that the tapered part 15' permits its coming out without the exercise of any effort in the act of removing it.

While I have herein shown a single embodiment of my invention for the purpose of clear disclosure, it will be manifest to persons skilled in the art, that considerable variation may be made in the general arrangement and configuration of the parts within the scope of the appended claims.

Having described my invention what I claim as new and desire to secure by Letters Patent is:—

1. The combination of a collapsible cup for receiving a collapsible lubricant container; a collapsible lubricant container insertable in the cup and having a rigid perfor-

rate end wall; means to clamp said end wall and side wall of the container in the cup and means to contract both receptacles.

2. A cup, to receive a collapsible container, having an outwardly flared screw, threaded, open end and a correspondingly flared threaded closure, in combination with a collapsible container, having an outwardly extending circumferential extension near its bottom end to be clamped between the flared end of the cup and its closure and having an opening in its bottom, and a plunger in the cup to collapse the container.

3. A cup having an axially movable piston therein and an outwardly flared screw threaded, open end forming an oblique shoulder; a threaded closure for the cup having a parallel circumferential shoulder at its periphery; a container of cylindrical form having a relatively fixed centrally perforated bottom wall of larger diameter than the main body part of said container, the side wall of the body at the bottom end thereof, being extended around the edge of the bottom wall, thereby forming an extension to be clamped between the shoulder of the cup and of its closure when the parts are screwed together and a piston in the cup, axially movable to discharge the contents of the container by collapsing the container and a valve in the discharge end of the cup.

4. In combination with a cup, a collapsible container insertable in the cup and having a centrally disposed discharge opening and means in the cup to clamp the container at all points around the opening.

5. A collapsible container of cylindrical form having a bottom wall thicker than its side wall and larger in diameter to form a circumferential projection by which to clamp it within a cup.

6. A one-piece cup shape collapsible container having a bottom wall centrally perforated and thicker than the side wall whereby to hold the container in the cup.

7. A one-piece, cup-shape collapsible container having a relatively thin collapsible side wall; a thick perforate end wall, the side wall extending around the edge of the end wall, and a closure for said perforation.

In testimony whereof I hereunto subscribe my name.

FREDERICK W. VODOZ.
